DISPENSING HEAD FOR A PRESSURIZED CONTAINER

Robert P. Vuillemenot, Oradell, N.J., assignor to The Procter & Gamble Company, Cincinnati, Ohio, a corporation of Ohio

Filed Apr. 4, 1963, Ser. No. 74,289

Term of patent 14 years

(Cl. D58—26)

Fig. 1

FIG. 1 is a side elevational view of a dispensing head for a pressurized container showing my new design.
FIG. 2 is a rear elevational view thereof.
FIG. 3 is a top plan view thereof.
FIG. 4 is a front elevational view thereof.

I claim:
The ornamental design for a dispensing head for a pressurized container, as shown.
